H. J. LONG

THERMOSTATIC BURNER CONTROL

Filed August 13, 1923

FIG. I.

FIG. III.

FIG. IV.

FIG. V.

FIG. VI.

INVENTOR:
HERBERT J. LONG
by his attorney
John B. Muller

Patented Nov. 16, 1926.

UNITED STATES PATENT OFFICE.

HERBERT J. LONG, OF NEW BRUNSWICK, NEW JERSEY, ASSIGNOR TO THE KOMPAK CO., OF NEW BRUNSWICK, NEW JERSEY.

THERMOSTATIC BURNER CONTROL.

Application filed August 13, 1923. Serial No. 657,082.

My invention pertains to a thermostatic burner control and more particularly to a construction in which the burner proper which is supplied with flame orifices itself constitutes one of the co-acting elements of the thermostatic mechanism whereby the latter functionates to close a valve and cut off the supply of fuel in the burner construction whenever the burner is not ignited.

10 This application comprises subject matter divided from my parent application entitled "Emergency fuel valve control appliance" issued September 4, 1923, as Patent No. 1,467,049, together with minor details of 15 construction which for some purposes may be considered as improvements. The underlying principle of operation is the same as that originally shown, described and claimed in my earlier application above identified.

20 The drawings exemplify a thermostatic burner control adapted for employment as a pilot burner in a hot water heater. A brass connection is made with a gas supply pipe so as to project upwardly therefrom. De-

25 tachably fitted in the brass connection is a tube of Monel metal provided intermediately of its ends with circumferentially arranged holes in which are seated spuds through which fuel may escape and be ignited.

30 The brass connection is fashioned interiorly with a valve seat and a rod is passed through the Monel tube and at its lower end carries a valve adapted to cooperate with said seat. The rod is composed of metal having a lesser coefficient of expansion than that of the Monel tube and its normal position with reference to the latter is controlled by an adjusting agency carried by the closed upper end of the Monel tube. Ordinarily,

35 when the pilot burner is not ignited the valve will be closed, but when the parts are subjected to the heat of the pilot flame the Monel tube will expand and hold the valve raised from its seat. The rod may also be manually lifted from its seat against the action of a spring. Just above the flame orifices I fit a sleeve provided with a flange intended to serve the function of a baffle to prevent the formation of carbon.

40 Adverting to the drawings:

Figure I is an elevation of a thermostatic burner control embodying my invention the same being shown in connection with a gas supply pipe.

Figure II is mainly a longitudinal section of Figure I with the valve held open by flames.

Figure III is a view corresponding to Figure II showing the valve closed.

Figure IV is a longitudinal section of a modification corresponding with the form shown in Figure I of my parent application.

Figure V illustrates another modification corresponding to Figure X of my parent application.

Figure VI is a further modification corresponding with Figure V of my parent application.

Figure VII is still another modification showing the principle of my invention applied to a different type of burner.

Figure VIII illustrates a modification showing a nozzle torch in combination with my thermostatic burner.

I am familiar with the disclosures of the following prior patents: McCormick No. 269,083 of December 12, 1882, Franke No. 581,707 of May 4, 1897, Oeklke No. 643,363 of February 13, 1900, and Yockey et al No. 895,136 of August 4, 1908.

The form of my invention shown in Figures I to III inclusive is adapted and has for some years been successfully used as the pilot burner of a hot water heater. Its structure includes a brass tube 1 connected with a gas supply pipe 2 by means of a union 3. The tube 1 is fashioned interiorly with a valve seat 4 whereas its upper end is in threaded connection at 5 with a tube 6 composed of Monel metal and provided intermediately of its ends with five circumferentially arranged ports 7 in which are fitted spuds 8. The spuds 8 are brass or some other metal which has less affinity for carbon than has Monel metal. Aluminum or lava spuds might be employed instead of the brass spuds. The top of the Monel tube is provided with a single centrally located aperture 9 in which is slidably an adjusting rod 10 carrying at its upper end a ring 11. Interiorly of the tube 6 the lower end of the rod 10 carries a nut 12 for controlling the compression of a spring 13 which surrounds the rod 10 between the nut 12 and the upper end of the tube 6. An adjusting nut 14 operates with the rod 10 outside of the tube 6 so that the expansion of the tube will vary.

ously lift the nut and hence the rod. Connected with the inner end of the rod 10 is a rod 15 having detachably connected at its lower end a valve 16 adapted to fit the seat 4 and normally held thereagainst by the action of the spring 13 whereby passage of gas through the pilot burner is prevented. The purpose of the ring 11 is to facilitate manual lifting of the rod 10 and hence of the valve 16 from its seat against the action of the spring 13 so as to let gas escape from the ports or flame orifices 7 preparatory to igniting it and so that its flames as shown in Figure II will heat the burner, cause the Monel tube 6 to expand and thereby continue to hold the valve 16 open.

Fitted around the tube 6 is a brass collar 17 provided at its lower end with a flange 18 located just above the spuds 8 and adapted to act as a baffle to carry the tips of the white flames away from the metal and incidentally to prevent extinguishment of the flames under strong updraft.

The pilot burner is normally closed as shown in Figure III but when ignited its valve 16 is held in its open position. If the pilot burner for any reason becomes extinguished, the Monel tube 6 upon cooling contracts to move the rod 15 downwardly and press the valve 16 against its seat. The several adjustments afforded permit the proper seating of the valve 16.

In the modification shown in Figure IV a T 19 to which gas is supplied is fashioned with a valve seat 20 enclosed by a tube 21 fashioned near its top with orifices 22. Detachably connected with the upper end of the tube 21 is another expandible tube 23 provided at its top with a cap 24 with which a stem 25 has threaded connection at 26. The lower end of the stem 25 carries a needle valve 27 adapted, when the pilot burner is cold to close the outlet of the T 19.

Figure V illustrates a further modification in which a single expandible tube 28 has flame orifices 29 and in screw threaded connection with it at its top a plug 30 through which a stem 31 passes for slidable movement. The lower end of the stem is fashioned as a needle point 32 adapted normally to close the upper end of the bore 33 in a nipple 34 in response to the action of the spring 35.

Figure VI shows a gas supply pipe 36 with which a hollow structure 37 is detachably connected. The upper end of the structure 37 is provided with flame orifices 38 and just below with a partition 39 fashioned with a central port 40 adapted to be opened or closed according to the position of a stem 41 having its upper end fashioned as a needle point 42 and movable in a guide 43 in response to the action of a spring 44 which surrounds its lower end and tends to press up a collar 45. When the hollow structure 37

expands the port 40 will be carried up beyond the upper limit of the range of movement of the needle point 42.

Figure VII illustrates a horizontal type of burner provided with a gas inlet 46 leading to a chamber 47 having on one side a valve port 48 and on its other side a stuffing box 49 through which latter a needle pointed steel rod 50 projects for cooperation with the port 48. The chamber 47 communicates through the port 48 when open with another chamber 51 which is connected with a burner 52 having gas outlet ports 53 and at its further end having a depending extension 54 with which the opposite end of the steel rod has a slidale adjustable connection at 55. The burner 52 may be of any material because, when gas issuing from the ports 53 is ignited, it will always be very much hotter than the rod 50 in consequence of which it will expand enough to withdraw the valve extremity of the rod 50 from the port 48.

Figure VIII shows the application of the principle of connecting with a gas supply pipe 59, a nozzle torch 62^a according to the showing of Figure III in my parent application, with the additional showing of a push button valve 73 for controlling the communication through the pipe 59. It will be observed that the mouth of the torch is directed toward the pilot burner so that when gas issuing from the torch is ignited it will soon heat the pilot thermostat sufficiently to open the pilot burner. The general form of the thermostatic pilot burner is like that shown in Figure IV to include a valve casing 60 and push button valve 73, a coupling 61^a, a gas line 71, a seat 62 enclosed by a tube 63 having orifices 64 and above another tube 65 provided with a cap 66 through which passes an adjustable stem 68 provided with a squared end 67 and surrounded by an adjusting nut 70. The lower end of the stem 68 carries a needle valve 69.

I claim:—

1. A gas burner comprising a tube provided with an inlet and a flame orifice, a composite rod structure projecting into said tube and having one part adapted to close said inlet, a spring normally tending to move said rod structure toward the inlet capable of being closed thereby, means for limiting such movement of said rod structure, said rod structure extending out of said tube to enable its manipulation against the action of said spring to open said inlet, said tube and rod structure having different coefficients of expansion whereby any heat generated by the flame against said tube will hold the inlet and the rod structure in their open relationship.

2. A gas burner comprising a tube provided with an inlet and a flame orifice, said inlet being fashioned as a valve seat, a valve rod projecting into said tube and carrying a

valve adapted to fit said seat, a spring normally tending to move said rod toward its closing position, means for limiting such movement of said rod, said rod extending 5 out of said tube to enable its manipulation against the action of said spring to open said valve, said tube having a greater coefficient of expansion than said rod whereby the heat generated, so long as gas issuing from said 10 orifice is lit, will cause said valve to be held off of said seat and thus insure the flow of gas.

3. A thermostatic gas burner comprising a hollow structure provided with a valve 15 seat and a flame orifice and adapted to expand in response to the heat from a flame at its orifice, a valve device carried by and having a lesser coefficient of expansion than said structure such that a relative differential action 20 occurs in response to changes in temperature whereby to control the flow of fuel past said valve, and a baffle carried by said hollow member in proximity to said orifice.

4. A gas burner comprising a tube provided with an inlet and a flame orifice and

furthermore fashioned interiorly with a valve seat, a valve stem projecting into said tube and carrying interiorly a valve adapted to cooperate with said seat and a nut adjustably carried by an exterior portion of said stem, said tube having a greater coefficient of expansion than said stem whereby applied heat will cause said tube to raise said nut and hold said valve off of its seat.

5. A gas burner comprising a hollow structure provided with an inlet and a flame orifice and furthermore fashioned interiorly with a valve seat, a valve structure projecting into said hollow structure and adapted to cooperate with said seat and a nut adjustably carried by an exterior portion of said valve structure, said hollow structure having a greater coefficient of expansion than said valve structure whereby applied heat will cause said hollow structure to expand 45 and press against said nut and hold said valve structure off of its seat.

Signed by me, this 17th day of July, 1923.

HERBERT J. LONG.
